UNITED STATES PATENT OFFICE

SHELDON L. POLLOCK, OF NEW YORK, N. Y.

DESIGN FOR A POCKET CHECK PROTECTOR OR SIMILAR ARTICLE

Application filed January 19, 1932. Serial No. 42,544. Term of patent 7 years.

To all whom it may concern:

Be it known that SHELDON L. POLLOCK, citizen of the United States, and resident of New York city, in the county of New York and State of New York, has invented a new, original, and ornamental Design for Pocket Check Protector or Similar Article, of which the following is a specification, reference being had to the accompanying drawing, forming part thereof, in which,

Fig. 1 is a plan view of one side of a check protector embodying my new design, the opposite side thereof being identical with the side shown; and

Fig. 2 is a side elevational view thereof.

I claim:

The ornamental design for pocket check protector or similar article substantially as shown and described.

Dated, New York city, January 16th, 1932.

SHELDON L. POLLOCK.
